UNITED STATES PATENT OFFICE.

JAMES E. KEMPH, OF WASHINGTON, DISTRICT OF COLUMBIA.

FLYING MACHINE.

Application filed May 28, 1923. Serial No. 641,859.

To all whom it may concern:

Be it known that I, JAMES E. KEMPH, a citizen of the United States, residing at Washington, District of Columbia, have invented certain new and useful Improvements in Flying Machines, of which the following is a specification.

This invention has reference to the type of airplanes known as ornithopters, and its object is to provide a flying machine, which may sustain itself in the air by the reaction of the air upon the flying machine, without the aid of sustaining mechanism, except as hereinafter explained.

15 The invention, because of its peculiar construction, I call an orniplane.

The object of the invention is to provide a flying machine having a superior means for its propulsion through the air, and the 20 invention comprises in itself a construction inherent therein for the maintenance of lateral balance while in flight.

The invention will be best understood from a consideration of the following detailed description taken in connection with the accompanying drawings forming part of this specification with the understanding, however, that the invention is not confined to any strict conformity with the showing in 25 the drawings but may be changed and modified so long as such changes and modifications mark no material departure from the salient features of the invention as expressed in the appended claims.

30 In the drawings:

Figure 1 is a side elevation of a flying machine comprising the invention.

Figure 2 is a section on the line 2—2 of Figure 1.

40 Figure 3 is an end view of the flying machine.

Figure 4 is a section on the line 4—4 of Figure 2, and

45 Figure 5 is a detail view of the primary and steering lever of the flying machine.

Referring to the drawings, there is shown a fuselage 1, supported intermediately of its length, upon a truck 2, at the rear end, by a runner 3. The fuselage is provided with 50 horizontal stabilizers 4, at the rear end thereof, and hingedly connected to the rear end of the stabilizers, are elevators 4', whereby the machine may be raised or lowered, as desired.

55 At the rear, the fuselage is also provided with a vertical stabilizer 7, and hingedly

connected to the rear edge thereof is the usual rudder 5, in the intermediate portion of the body of the fuselage, there is a cockpit 8, in which is located a seat 9 having 60 a lever for shoulder supports 10, so arranged that the operator may tip the shoulder supports to one side or the other, to operate the ailerons and also the propelling wings 11 may be controlled by the operator occupying 65 the seat 9 to cause movement of the planes or units 12 and 13 to the closed and open position while a steering wheel 14 is arranged within easy reach of the operator occupying a position in the seat 9. 70

The wheel 14 is mounted on a shaft 15 carried by a truss frame or primary lever 16 having connecting links 17, in turn connected to the movable wings 11. Extending along the fuselage are wires 18 and 18' connected to the elevators and rudder 4' and 5 respectively, so that the elevator and rudder may be independently controlled. The planes or units 12 and 13 are connected by hinges 20 at the forward edge to frame 75 of movable wings 11, so that the planes or units will rise or fall under the action of air currents engaging them and rising currents will cause the planes or units to be arrested by engagement with the frame 80 of propelling wings 11 also on moving about the support pin 20. By this means the rear of the planes or units have a natural tendency to gravitate downwardly 85 on their axis away from the higher wings 90 but are urged upward by the rising currents of air engaging under the planes or units. When the flying machine is underridden by the air currents, the propelling wings 11 are 95 raised to a higher level as indicated by the lines 21 and when the propelling wings are no longer supported by the rising air currents the propelling wings drop to a lower level, allowing the air currents to flow 100 downwardly therethrough, by the automatic opening of the planes.

There is provided an upper wing 22 of a lateral extent approaching the spread of the wings or planes of the vehicle and such upper wing has ailerons 23 with horns 24 and operating wires 25 for tilting the ailerons as needed.

The operator sits with his feet braced against the rudder control lever and his hands grasping the steering wheel 14 on the primary lever. The body of the operator is then in a position between the arms 110

of the lever that control the ailerons. By pressure of either foot on the rudder control lever, the machine is directed to the right or left as desired, in a horizontal plane. By 5 turning the wheel 14 mounted on the primary lever, the flying machine is directed up or down in a vertical plane by the elevators. The right or left movement of the body causes the lever controlling the 10 ailerons to move such ailerons as desired for the purpose of assisting or maintaining lateral balance.

When the operator grasping the wheel 14 moves the same, so that the frame 16 is 15 rocked on its mounting, the wings 11 will be moved on their pivots through the connecting link 17, so that when the wheel 14 is pulled toward the operator, the wings 11 will be moved on the hinges 19, so that the 20 wings are dropped or lowered with respect to the fuselage, while, when the wheel 14 is pushed away from the operator, for rocking the frame 16, in the opposite direction, the wings 11 will be raised to an upper 25 position, at an opposite dihedral angle to that assumed in the lower position, in order to effect the flying of the plane, as will be hereinafter described.

Assuming the present invention to be applied 30 to a form of "orni-plane" of the well known glider type, they will operate in the following manner, in the use of this type of plane.

In beginning an ascent, the wings are 35 quickly forced to the lower position by the wheel 14 being drawn toward the operator. In this movement, the wings offer their full under surface as a propelling and lifting force, following which the wings are quickly 40 returned to horizontal position by pushing the wheel 14 forward, and in order that the wings will feather through the air on their return to normal position, the units or planes 12 and 13 open, in order to offer the 45 least resistance to the forward movement of the machine. This movement of the wings is continued or repeated a few times until sufficient speed and momentum are obtained to raise the plane from the ground. As the 50 speed of the machine on the ground increases to the point that the air resistance is sufficient to support the same, the operator moves the wheel 14 in a circular motion to the right, causing the elevators to function 55 upward to effect a resistance to the air, which will cause the plane to be immediately raised into the air for beginning the flight. As long as there are sufficient upward air currents for supporting the plane, the wings 60 11 are retained in the upper position, in which they may be adjusted for varying the dihedral angle, in order to offer a greater or less resistance to the forward movement of the plane, which would effect a correspondingly greater tendency to raise or ele-

vate the plane, when the wings are at a great dihedral angle, while a mere supporting action will be exerted thereby when the planes are in substantially the same plane. In this way, it will thus be seen that strong 70 air currents may be utilized by the operator in obtaining an ascent of the plane, by increasing the upper dihedral angle of the wings, and when said currents are not sufficiently strong, the dihedral angle may be 75 decreased, or the wings positioned in the same plane, for maintaining a supporting action, but at the same time permitting the free forward movement, so that sufficient speed may be maintained for utilizing a 80 subsequent stronger upper air current, for further use in effecting an additional ascent of the plane. If, during the course of flight, a downward air current is encountered, the wings will again be caused to 85 swing on the hinges 19, as in starting, so that the descent of the plane will be reduced to a minimum, while the same is passing through the descending air current.

When it is desired to descend, the wheel 90 14 is moved to the left in a circular motion, and when the "orni-plane" reaches a position preparatory to landing, an upward movement of the wings to a substantially 95 great dihedral angle in the upper position 100 will effect a resistance to the forward motion of the plane for retarding the speed, in addition to the usual operation of the elevator to enable the operator to effectively land the plane in a shorter distance than 105 would otherwise be possible.

From the above description, it will, therefore, be clear that the wings may be utilized in a number of different ways, in connection with a glider as above described, and in a 105 similar manner in connection with any other suitable form of heavier than air planes, for effecting the efficient maneuvering, and also for providing a balance of the machine. When the wings are in the upper position, 110 and arranged at a dihedral angle, it will be further noted that a balancing action will be effected for steadyng the flight of the plane.

What I claim as new is:

1. In combination, an aeroplane having a fuselage provided with a cock pit for the operator, elevating planes for controlling the ascent or descent of said plane, and means for operating the elevating plane, a 120 pair of wings hingedly mounted on said aeroplane on axes inclined with the line of flight in the same horizontal plane at opposite sides of the aeroplane, said axes diverging rearwardly, each of said wings having a 125 plurality of units hingedly connected thereto, at right angles to the line of flight and limited in their movement by the wings, a lever pivotally mounted in the cockpit of said aeroplane, and connections between said 130

lever and said wings for effecting a movement of the wings in the movement of the lever to position the wings in cooperation in one position for effecting a balancing, supporting and elevating action on the aeroplane, and into a non-supporting relation in another position.

2. In combination, an aeroplane having a fuselage provided with a cock pit for the operator, elevating planes for controlling the ascent or descent of said plane, a lever pivotally mounted in the cock pit of said plane, a steering wheel rotatably mounted on said lever, operating connections between the elevating planes and the steering wheel for operating said planes in the rotation of the steering wheel in either direction, wings movably mounted on said aeroplane, and connections between said lever and said wings for effecting a movement of the wings in the movement of the lever, to position the wings into cooperation in one position for effecting a balancing, supporting and elevating action on the aeroplane, and into a non-supporting relation in another position.

3. In combination, an aeroplane having a fuselage structure formed with a cock pit

and projecting frames at opposite sides thereof terminating in outwardly and rearwardly diverging end portions, a lever pivotally mounted in the cock pit, a steering wheel rotatably mounted on said lever, elevating planes mounted on said fuselage, connections between said elevating planes and said steering wheel whereby a rotation of the steering wheel in either direction will operate said elevating plane, wings hingedly connected to the rearwardly and outwardly diverging ends of the frames projecting, from said fuselage, and operating connections between said lever and said wings for effecting a movement of the wings on a hinged connection in a rocking movement of the lever adapted to move said wings into cooperative relation above the horizontal plane of the hinged connection, for effecting an elevating, balancing, and supporting action, in connection with said aeroplane, said lever being operable to move said wings below the plane of said hinge connections whereby they will have a non-supporting action on said planes.

In testimony whereof I affix my signature.
JAMES E. KEMPH.
